(57) **CLAIM**

The ornamental design for an endoscope with oblique tip, as shown and described.

DESCRIPTION

FIG. 1 is a perspective view of an endoscope with oblique tip showing our new design;

FIG. 2 is a partial enlarged view of the claim corresponding to the section shown in FIG. 1.

FIG. 3 is a front view of the endoscope thereof;

FIG. 4 is a back view of the endoscope thereof;

FIG. 5 is a right side view thereof;

FIG. 6 is a left side view thereof;

FIG. 7 is a top plan view thereof; and,

FIG. 8 is a bottom plan view thereof.

The dashed broken lines in the drawing depict environmental subject matter only and form no part of the claimed design. The dash-dot-dash lines represent the border for the enlarged partial view and form no part of the claimed design. The sheath and endoscope with oblique tips is shown with a symbolic break in its length. The appearance of any portion of the article between the break lines forms no part of the claimed design.
